UNITED STATES PATENT OFFICE.

OSCAR O. R. SCHWIDETZKY, OF HASBROUCK HEIGHTS, NEW JERSEY, ASSIGNOR TO
BECTON DICKINSON & CO., OF RUTHERFORD, NEW JERSEY.

SYRINGE.

1,315,164.

Specification of Letters Patent. Patented Sept. 2, 1919.

Application filed July 3, 1919. Serial No. 308,412.

To all whom it may concern:

Be it known that I, OSCAR O. R. SCHWIDETZKY, a citizen of the United States, and a resident of Hasbrouck Heights, in the 5 county of Bergen and State of New Jersey, have invented a new and Improved Syringe, of which the following is a full, clear, and exact description.

The invention relates to syringes having 10 a barrel provided at one end with a nozzle and at the other end with a rubber bulb for drawing liquid into the barrel and ejecting it through the nozzle to any part.

The object of the invention is to provide 15 a new and improved syringe of this type arranged to permit the user to readily draw liquid into the barrel and to prevent the drawn in liquid from flowing into the bulb on holding the syringe with its nozzle upward. Another object is to permit the user 20 on pressing the bulb to force air out of the bulb into the barrel and to allow the air to return to the bulb and re-inflate the same on releasing the pressure of the bulb. 25 Another object is to provide a valveless syringe composed of but two parts which can be readily assembled or disassembled for cleaning and sterilizing purposes.

With these and other objects in view, the 30 invention consists of certain novel features of construction, as hereinafter shown and described and then specifically pointed out in the claims.

Figure 1 is a sectional side elevation of 35 the syringe with a liquid drawn into the barrel;

Fig. 2 is a similar view of the same with the nozzle pointing upward; and

Fig. 3 is a sectional plan view of the 40 same on the line 3—3 of Fig. 2.

The barrel 10 is preferably made of glass and is provided at its forward end with a nozzle 11 and at its rear end with a flaring mouth 12 on which is seated a rubber bulb 13 having an integral neck 14 extending into the rear end of the barrel adjacent the mouth 12. The neck 14 of the rubber bulb 13 is provided with an end wall 15 which closes the neck 14. The peripheral surface 45 of the neck 14 is provided with one or more minute grooves 16 each of which forms with the corresponding inner surface of the barrel 10 an air passage. The bulb 13 is provided in its wall adjacent the end wall 15 with an opening at the end of the

corresponding air passage formed by the groove 16 and the inner surface of the barrel 10, and by this arrangement communication is established between the interior of the bulb 13 and the barrel 10, that is, by 60 way of the corresponding opening 17 and its groove 16. It will be noticed that by the arrangement described, the end wall 15 of the neck 14 forms a large supporting surface for the liquid to rest on at the time 65 the barrel 10 is held in position with the nozzle 11 upward so that the liquid is not liable to flow through the air passage and the opening 17 into the bulb 13.

It is understood that on using the syringe, 70 the operator first squeezes the rubber bulb 13 to allow the air contained therein to pass into the barrel 10, and the nozzle 11 is now immersed in the liquid after which the operator releases the bulb 13 to draw the liquid 75 into the barrel 10, and to permit the air in the barrel to pass into the bulb 13 to re-inflate the latter. The operator can now turn the syringe upside down or into any inclined position without danger of the 80 liquid flowing from the barrel into the bulb 13. It is understood that the syringe is usually held temporarily in this position and the liquid has not time to pass into the bulb through the minute grooves 16 and the openings 17 especially as a large supporting surface for the column of liquid is provided by the wall 15. It will also be noticed that owing 85 to the capillary action of the inner surface of the barrel at the air passage any 90 liquid is prevented from flowing through the air passage and the openings 17 into the bulb 13. In syringes having a rubber bulb it is desirable that medicated or other liquid 95 does not pass into the bulb to avoid deterioration of the bulb by the influence of the medicated liquid. It will also be noticed that the liquid is contained in the barrel and hence the user of the syringe can see at 100 all times whether the medicated liquid is in proper condition or not.

The improvement is shown applied to syringe barrels but it may be applied to the suction bulb of a breast pump or a similar apparatus to prevent the milk drawn from the breast to pass into the bulb. It will 105 also be noticed that by providing a minute air passage the suction action is retarded and hence the milk is slowly drawn from the breast thus preventing undue pain.

Having thus described my invention, I claim as new and desire to secure by Letters Patent:—

- 5 1. A syringe and similar apparatus, comprising a barrel having at one end a nozzle and being open at the other end, and a compressible bulb having a closed integral neck fitting into the said open end, the said neck being provided on its peripheral face with minute grooves each forming with the barrel an air passage, the said bulb being provided in its wall adjacent the said neck and at the end of the said air passage with an opening establishing communication between the interior of the bulb and the said air passage.
- 10 2. A syringe and similar apparatus, comprising a barrel having at its front end a nozzle and being open at the rear end, and a compressible bulb having a neck fitting into the open rear end of the barrel and provided with an end wall closing the neck, the latter being provided exteriorly with a minute groove forming with the opposite inner surface of the barrel an air passage

terminating a distance from the open end of the barrel, the wall of the bulb being provided with an opening located in the rear of the said neck wall and connected with the rear end of the said air passage to establish communication between the interior of the bulb and the interior of the barrel by way of the said opening and the said air passage.

- 15 3. A syringe and similar apparatus, comprising a barrel having a nozzle at the end and having a flaring mouth at the other end, a compressible bulb seated in the said mouth and having a closed neck fitting into the barrel adjacent the said mouth, the neck being provided exteriorly with a groove forming with the barrel an air passage, the said bulb having an opening through its wall adjacent the said neck and at the end of the said passage to establish communication between the interior of the bulb and the interior of the barrel by way of the said opening and the said air passage.

OSCAR O. R. SCHWIDETZKY.
